UNITED STATES PATENT OFFICE

JOHN A. EBERLE, OF ST. LOUIS, MISSOURI, ASSIGNOR TO THE PERFECTION MANUFACTURING COMPANY, OF ST. LOUIS, MISSOURI, A CORPORATION OF MISSOURI

CHILD'S WALKER

Application filed November 20, 1925. Serial No. 70,278.

My invention relates to new and useful improvements in children's walkers of the type used for infants in teaching them to walk.

The object of my invention is to provide a walker which may be readily collapsed to permit easy handling when not in use.

A further object is to provide an adjustable seat to eliminate the necessity of manufacturing various sizes.

10 A still further object is to provide a removable folding handle which permits the walker to be used as a go-cart, if desired, and yet does not substantially increase the bulk when folded.

15 With the foregoing and other objects in view, my invention consists in certain novel features of construction and arrangement of parts, hereinafter more fully described and claimed, and illustrated in the accompanying drawings, in which—

Figure 1 is a perspective view of my improved walker with the handle attached.

Figure 2 is a side view of the walker collapsed.

20 Figure 3 is a rear view of the walker.

Figure 4 shows the handle in folded position.

The numerals 1 and 2 in the drawings indicate the front legs of the walker. These 30 members flare outwardly and forwardly and have mounted on their lower extremities wheels 3 and 4 of the caster type. A cross-piece 5 joins legs 1 and 2 together and extends along the flared portions to form a reinforcing piece. The rear legs 6 and 7 flare outwardly and backwardly near their lower ends and together with cross-piece 8 carry an axle 9. The rear cross-piece 8 joins the legs 6 and 7 together and is then bent downwardly to act as reinforcement and aid in carrying the axle. Wheels 10 and 11 are mounted on the ends of axle 9.

40 The upper ends of legs 1 and 6 and 2 and 7 are joined together by arched strips 12 and 13, respectively. These arched strips are riveted to the legs tightly enough to form a solid connection and yet sufficiently loose to permit pivotal movement. A circular body supporting strip 14 is bolted between the two 45 arched strips 12 and 13. Rubber tubing 15 or

other suitable cushioning material is used to cover the body supporting strip in order to protect a child from direct contact with the metal when the walker is in use.

Intermediate their ends a seat supporting 55 strip 16 joins the front legs together. The ends of this strip are bent at right angles to provide a flat surface through which a rivet may be passed and also to make this member adjustable as to height. The rivets holding this piece are loose enough to permit its being turned and since the main body portion is not aligned with the axis of the rivets carrying it, it may be rotated and set at two different 60 heights.

A similar piece 17 joins the back legs 6 and 7. This piece may also be rotated on the rivets which hold it to change the height as shown by the dotted lines in Figure 3 of the drawings. Side strips 18 and 19 join each 70 pair of front and rear legs and are held in place by the same loose rivets that carry the seat supporting members 16 and 17.

65 A seat 20 of wood or any other suitable material is removably bolted to the seat supporting members 16 and 17. It is necessary to make the seat removable because when the seat supporting strips are rotated to change their height, the seat is refastened to the reverse sides of these strips.

75 The loosely riveted joints at the middle portions and upper ends of the legs permit the walker to be collapsed and folded into the position shown in Figure 2. Toggle joints 21 and 22 join the rear legs 6 and 7 to 85 the side pieces 18 and 19, respectively. These joints serve to lock the parts in an upright position.

80 A handle 23 is formed of the same strip material as the rest of the vehicle. The lower end 24 of handle 23 is bifurcated and provided with notched ends 25 which are adapted to engage openings on either side of the seat in the seat supporting member 16. The handle has a pivotal connection near its middle 90 and is provided with a bolt 26 to lock it in extended position. The upper end 27 flares out into a suitable handle.

95 The herein-described walker with the exception of the rear axle and seat is formed 100

entirely of strip metal suitably bent to form various parts. It is economical to manufacture, and provides a suitable vehicle to be used as a walker or toddler in the house, in which case the handle is removed and is equally well adapted to be used as a go-cart on the street.

Reference has been made throughout the description to the use of rivets which are not absolutely tight at all points where a pivotal movement is desired. It is entirely feasible and in some cases preferable to insert washers between the strips at these pivotal connections in which case the rivets may be driven tightly home.

15 I claim:

20 A child's vehicle including upright members, rotatable seat supporting members joining said upright members, the main portions of said seat supporting members being 25 beyond their axes of rotation, and a seat, said seat being adjustable as to height by the rotation of said seat supporting members.

In testimony whereof I hereunto affix my
25 signature this 16th day of November, 1925.

JOHN A. EBERLE.
